United States Patent Office

Des. 198,858
Patented Aug. 11, 1964

198,858

SLED

Leonard E. Greenberg, West Hartford, Conn., assignor to Coleco Industries, Inc., Hartford, Conn., a corporation of Connecticut

Filed Mar. 18, 1964, Ser. No. 79,058

Term of patent 14 years

(Cl. D34—15)

FIG 1

FIG 2

FIG. 3

FIG. 4

FIG. 5

FIGURE 1 is a perspective view of a sled showing my new design;

I claim:

The ornamental design for a sled, as shown.
